COMBINED BOTTLE AND DISPENSING CUP

Donald E. Dailey, Evansville, Ind., assignor to John H. Breck, Inc., Springfield, Mass.

Filed Feb. 6, 1962, Ser. No. 68,681

Term of patent 14 years

(Cl. D58—8)

FIGURE 1 is a perspective view of a combined bottle and dispensing cup, showing my new design;

FIG. 2 is a perspective view of the dispensing cup, same being shown in an inverted position; and

FIG. 3 is a top plan view of the combined bottle and dispensing cup.

The characteristic features of my design reside in a dispensing cup having straight side walls and a flat top connected by a restricted neck portion in combination with a bottle all as shown.

I claim:

The ornamental design for a combined bottle and dispensing cup, as shown and described.
